UNITED STATES PATENT OFFICE.

JULIUS W. STOFFEL, OF MASCOUTAH, ILLINOIS.

WATER-HEATER FOR GASOLINE-STOVES.

SPECIFICATION forming part of Letters Patent No. 301,016, dated June 24, 1884.

Application filed June 23, 1883. (No model.)

To all whom it may concern:

Be it known that I, JULIUS W. STOFFEL, of Mascoutah, in the county of St. Clair and State of Illinois, have invented a certain new and useful Improvement in Water-Heaters for Gasoline-Stoves, of which the following is a full, clear, and exact description, reference being had to the accompanying drawings, forming part of this specification, and in which—
10 Figure 1 is a perspective view showing the top of a gasoline-stove and the heater arranged thereon. Fig. 2 is an enlarged perspective view of the heater, part broken away. Fig. 3 is a section of the vertical part of the circulating-pipe and the inclosing-tube. Fig. 4 is a detail section illustrating a valve that may be and preferably is used on the receiving end of the pipe. Fig. 5 is a similar view showing the valve located in the downturned end of 20 the pipe instead of in a thimble, as shown in Fig. 4.

My invention relates to detachable heaters that can be used on gasoline-stoves, and which will not in any way obstruct the fire, preventing it from being used for cooking or other purposes.

My invention consists in features of novelty hereinafter fully described and pointed out in the claims.

30 Referring to the drawings, A represents the top of an ordinary gasoline-stove.

B represents a vessel for containing water to be heated, which may rest on one side of the stove-top, as shown, or on an independent support.

C represents a pipe secured to and communicating with the lower part of the vessel B, and from the vessel it extends outward a suitable distance, where it is bent to form a loop, 40 as shown, and then returns to and enters the vessel, where it is turned upward, its end reaching quite or nearly to the top of the vessel, where it is closed, and provided with an opening, C', in the side. (See Fig. 3.) The loop of the pipe is intended to surround the burner of the stove, so that the water in the pipe is heated and caused to circulate therethrough, as shown by the arrows, Fig. 2. The pipe is preferably bent downward at C', so that

the loop will be below the upper surface of the 50 stove, (see Fig. 1,) so that the pipe does not in the least interfere with anything being cooked on the stove at the same time the water is being heated.

D represents a tube with a closed upper end, 55 which fits over the vertical part of the pipe, (see Figs. 2 and 3,) which causes the hot water to pass down to or nearly to the bottom of the vessel, and prevents the hot water being thrown over the edge of the vessel. This tube simply 60 fits over the top of the pipe, and may be removed to gain access to the vertical portion of the pipe and the inside of the tube for cleaning purposes.

The induction end of the pipe is preferably 65 provided with a ball-valve, I, located in a thimble, I', with an opening and seat, I'', (see Fig. 4,) or the end of the pipe may be turned downward and the ball located in it. When water is poured into the vessel, it rolls the valve 70 away from its seat and finds its level in the pipe C, and when the pouring of the water into the vessel ceases, the ball will roll by gravity and close the opening I'', so that the water in the pipe cannot return to the vessel except 75 through the opening C', (as it is expanded by being heated,) and as soon as a discharge takes place a fresh supply of water will enter the pipe from the vessel, the excess of pressure of the water in the vessel opening the valve, and 80 as soon as the pressure is equalized the valve will close, as described. Each time the valve opens and closes it makes a noise resembling the tick of a clock, and its function is to prevent the bubbling noise incident to its absence; 85 and there are certain other advantages arising from its use.

I claim as my invention—

1. A detachable water-heater for gasoline-stoves, consisting of a vessel to rest on or off 90 the stove, a pipe extending from the side of the vessel, down beneath the surface of the stove, to, around, and from the burner, and back, upward, and then through the side of the vessel, and finally upward to form a 95 straight vertical portion closed at top, having a perforation in its side, the whole constructed and arranged substantially as shown

and described, as and for the purpose set forth.

2. A water-heater for gasoline-stoves, consisting of a vessel to rest on or off the stove, a pipe extending from the side of the vessel to, around, and from the burner, having upturned discharge end, and a tube having closed upper

end, and placed over the discharge end to conduct the discharge to the lower part of the vessel, as set forth.

JULIUS W. STOFFEL.
